(57) **CLAIM**

The ornamental design for a package for bonding tools, as shown and described.

DESCRIPTION

FIG. 1 is a perspective view of a package for bonding tools showing my design;

FIG. 2 is a top view of the package;

FIG. 3 is a bottom view of the package;

FIG. 4 is a side view of the package;

FIG. 5 is another side view of the package;

FIG. 6 is a front view of the package;

FIG. 7 is a back view of the package;

FIG. 8 is a perspective view of package with the lid open;

FIG. 9 is a top view of the package with the lid open;

FIG. 10 is a bottom view of the package with the lid open;

FIG. 11 is a side view of the package with the lid open;

FIG. 12 is another side view of the package with the lid open;

FIG. 13 is a front view of the package with the lid open; and,

FIG. 14 is a back view of the package with the lid open.

The broken line showing in the figure drawings is included for illustrative purposes only and forms no part of the claimed design.
